CLAIM

The ornamental design for a light strip, as shown and described.

DESCRIPTION

FIG. 1 is a top perspective view of a light strip, showing my new design;

FIG. 2 is a bottom perspective view thereof;

FIG. 3 is a top view thereof;

FIG. 4 is a bottom view thereof;

FIG. 5 is a left side view thereof;

FIG. 6 is a right side view thereof;

FIG. 7 is a front view thereof;

FIG. 8 is a rear view thereof; and,

FIG. 9 is a partial enlarged view of FIG. 1.

The dash-dot-dash broken lines show the boundaries of the enlarged views and form no part of the claim thereof.

The light strip is shown with a symbolic break in its length. The appearance of any portion of the article between the break lines forms no part of the claimed design.
